(57) **CLAIM**

The ornamental design for a tire, as shown and described.

DESCRIPTION

FIG. 1 is a front top perspective view of a tire showing one embodiment of our new design.

FIG. 2 is a front view thereof; the rear view being a mirror image of the front view;

FIG. 3 is a left view thereof;

FIG. 4 is a right view thereof;

FIG. 5 is a top view thereof; the bottom view being a mirror image of the top view;

FIG. 6 is a side operational view showing the tire seen in FIGS. 1–5 in an alternate configuration of use.

FIG. 7 is a side operational view showing the tire seen in FIGS. 1–5 in an alternate configuration of use; and,

FIG. 8 is a rear operational view showing the tire seen in FIGS. 1–5 in an alternate configuration of use.

The features shown in broken lines are portions of the tire forming no part of the claimed design.

1 Claim, 8 Drawing Sheets
